UNITED STATES PATENT OFFICE.

CHARLES G. CONN, OF ELKHART, INDIANA.

CORNET.

1,218,057.

Specification of Letters Patent.

Patented Mar. 6, 1917.

Application filed November 3, 1914. Serial No. 870,133.

To all whom it may concern:

Be it known that I, CHARLES G. CONN, a citizen of the United States of America, residing at Elkhart, in the county of Elkhart 5 and State of Indiana, have invented certain new and useful Improvements in Cornets, of which the following is a specification.

The object of my invention is to provide means for extending the valve slides of a 10 cornet or trumpet, when the tuning slide is drawn; and with these and other objects in view my invention consists of the parts and combination of parts as will be hereinafter more fully set forth.

15 In the drawing:—

Figure 1 is a side elevation of a cornet embodying my invention;

Fig. 2 is a reverse side elevation of Fig. 1;

Fig. 3 is a bottom plan view of Fig. 1 with 20 the parts in normal position;

Fig. 4 is a similar view with the parts shown in extended position;

Fig. 5 is a detail view.

The reference numerals 1, 2 and 3 designate 25 finger key valves of any approved construction. 4 is the bell of the instrument and 5 the mouth pipe of the instrument.

The quick change or tuning slide 6 is illustrated in the drawings as forming a connection 30 between the mouth pipe and the finger valves, and to this slide is secured a rod 7, which is threaded at one end as at 8, and has a head 9. 10 is a nut on the screw threads 8 and adjustable thereon, and adapted to 35 operate with the fixed stop 11 mounted on the fixed tube 12, said stop 11 being provided with a hole in which the rod 7 slides. The opposite end of the rod 10 is secured to the tuning slide at 6^a. By setting the nut 10 at 40 different distances from the head 9, it will then be possible to determine beforehand the length of adjustment to be given to the slide 6, as the striking of the nut 10 against the stop 11 will prevent the further drawing out 45 of the slide.

The valve slides 13 and 14 slidably mounted in the valve crooks 15 and 16 respectively, are connected with the tuning slide so that they may be operated in unison with the 50 tuning slide, and such connection will now be described.

A pintle bearing 17 is rigidly secured to the crook 16 and on this bearing is pivotally mounted by means of the pin 18, a rocker 19. 55 20 is a link, one end of which is pivotally connected to the rocker, while the other end

is pivotally connected to the post 21 which is rigidly secured to the valve slide 13. 22 is another link, one end of which is pivotally connected to one end of the rocker 19, said 60 rocker being secured intermediate its ends to the post 23 which is rigidly secured to the valve slide 14. Beyond its connection with the valve slide 14, the link 22 is provided with pins or lugs 24 and 25 on both its upper 65 and lower face. The tuning slide 6 is provided with fingers 26, there being one above and one below the link 22, which are adapted, when the tuning slide is operated to contact with the pins 25 and 24 to move the 70 rocker when the tuning slide 6 is extended and returned to its normal position. It will be seen from Fig. 5 that the link 20 extends between the legs of the crook 27 of the center key finger valve between which I have 75 formed a slot bearing 28 for the link 20 for the latter to slide back and forth in when actuated by the rocker 19. With the parts in the position shown in Fig. 3, the instrument is set for its normal pitch. The screw nut 10 80 is adjusted on the bearing 7 for either high or low pitch and thus determines, upon the abutment of the nut against the stop 11, the length of travel of the valve slides.

Assuming that the screw nut 10 has been 85 adjusted as shown in Figs. 1 and 3 and it is desired to make a quick change to A, the tuning slide 6 is extended, thus bringing the fingers 26 into contact with the pins or lugs 25 on the link 22. Now a continued movement, in extending the tuning slide 6 results in said fingers 26 pulling the link 22 bodily in the direction of the extension and said link by reason of its connection 23 with the slide 14 extends this slide. While these 95 movements are taking place, the rocker 19 is rocked upon its pivot 18, thus causing the link 20 to be moved bodily in longitudinal direction, the link by reason of its pivotal connection 21, extending the slide 13. The 100 extension of all three slides 6, 13 and 14 is ultimately stopped when the nut 10 strikes the stop 11.

The tuning slide 6 is free to move a distance equal to the distance between the pins 105 or lugs 24 and 25 in both directions, without operating the links and rocker or the slides 13 and 14, thereby enabling me to adjust the tuning slide 6, whenever it is desired, without moving the other slides; but, as soon as 110 the fingers 26 contact with the lugs or pins 24 and 25 any further movement of the tun-

ing slide 6 results in an automatic adjustment of the slides 13 and 14 for a higher or lower pitch according to the direction in which the slides are moved.

5 By reason of my improved mechanism for adjusting the slides simultaneously, I am enabled to accurately and quickly adjust the instrument to a higher or lower pitch.

I claim:

- 10 A cornet having two valve slides and a quick change or tuning slide, a rocker pivotally mounted on the fixed portion of the cornet, a link connecting one end of said rocker to one of said valve slides and a 15 second link connecting the other end of said rocker to the second of said valve slides,

lugs on one of said links, and means carried by the quick change or tuning slide adapted to contact alternately with said lugs, whereby the rocker is operated during part of the 20 movement of the quick change or tuning slide to move the said valve slides, an adjustable stop being provided for the quick change or tuning slide to limit the movement thereof.

25 The foregoing specification signed at Elkhart, Indiana, this 13th day of October, 1914.

CHARLES G. CONN.

In presence of—

DESSA FLENAR,
HELEN HARRISON.
